DENTAL MATRIX RETAINER

Application filed October 29, 1929. Serial No. 403,288.

The present invention relates to retainer for a dental matrix, for supporting the matrix band while inserting it in and withdrawing it from the mouth and for tightening the band around the tooth body within the mouth.

A matrix as used in the dental arts is commonly considered as consisting of the combined band and retainer member, but for purposes of description herein, the parts are referred to separately as the band and the retainer.

As is well known, the purpose of a matrix is to horizontally surround the vertical walls of one or more teeth with a band so that a temporary improvised wall may be provided externally of the tooth.

Heretofore the matrix retainer most generally used by the dental profession and known as the "Hiniker matrix", has consisted of a threaded shaft having a pair of cooperating blocks mounted thereon, the first or lower block mounted in stationary placement at a lower end of the shaft and in which the lower end of the shaft is free to rotate, said shaft not being threaded through this lower block, but having at the end of the shaft a small riveted washer to prevent the lower end of the shaft from disengagement with the lower block. This lower block had mounted a pair of pins adapted to pass through a pair of openings transversely disposed adjacent each end of the matrix band, and thereafter said pins were adapted to pass through openings in the second block which was threadedly mounted on the shaft, so that by turning the shaft, the second or upper block was advanced toward the first or lower block, and thereby slidably engaging the pins, and thereafter contacting with the ends of the matrix band for the purpose of drawing the band tightly around the tooth.

Difficulty was encountered in the use of the existing retainers, due to the fact that the upper or reciprocable block frequently becomes unaligned with the band pins, due to lack of guiding means, and to correct this, some recent retainers have provided a guide for the reciprocable block, said guide consisting of a frame integrally made with the lower

block and extending parallel with the threaded shaft, and again turnably engaging the shaft adjacent the opposite end, thus providing a guiding face against which the butt face of the reciprocable block was in slidable contact.

This structure, however, did not provide any guides to prevent a sufficient transverse movement of said block to disalign the holes therein with the pins of the lower block; this structure also permitted and partially caused a frictional binding of the reciprocable block with relation to the threaded shaft; a further difficulty was that since the shaft freely turned in the lower block, a small washer had to be placed at the end of the shaft and riveted thereupon, and when the band was tightened around the tooth, all of the stress had to be borne by this delicately riveted shaft end with the result that the fastening frequently broke while in the mouth of a patient, necessitating re-arrangement of the matrix anew. This was very inconvenient because dental work is often done while a patient is enduring pain or is under an anesthetic, and speed is the essence of success.

Existing retainers also operate with a thread effective in one direction only, which requires twice as long to manipulate as a complementary thread effective in both directions.

The objects of this invention are to provide a matrix retainer wherein the blocks are guided one by the other, both longitudinally and transversely to precisely guide the band-holding pins into engagement with cooperating openings in the opposite block; to provide a more secure and effective base to receive the thrust of pressure when the matrix band is tightened around a tooth; to provide a quickly operated retainer, and to generally improve upon the present type of matrix retainer.

With the foregoing and other objects in view, the invention consists, broadly, in the novel construction, arrangement and form of parts, of a matrix retainer wherein the cooperating blocks are guided toward each other in simultaneous advancement, and wherein the pressure thrust on both blocks

is borne by the threads of the operating shaft.

A preferred form which the invention may take is illustrated in the accompanying drawings, to which reference is made, and in which like numerals indicate corresponding parts in the several views, and in which—

Fig. 1 is a side elevation of matrix retainer with blocks separated, and showing a matrix band surrounding a tooth.

Fig. 2 is a side elevation showing the blocks advanced centrally, with portions broken away,

Fig. 3 is a transverse vertical section on line 15 3—3 Fig. 1.

Referring to the drawings, 1 is an elongated threaded shaft being threaded substantially throughout its length, said threads being right hand throughout one portion, as at 20 2, and left hand at another portion 3, the division between direction of thread being preferably at approximately the longitudinal center 4 of the threaded portion of the shaft, said shaft having a squared end 5 at what 25 may be called an upper end and being butted at its opposite end 6, or what may be called the bottom end, the said butt being formed preferably integral with the shaft by axial indentation 7 forming the peripheral edges 30 outwardly.

Upon shaft 1, at one side of said longitudinal center 4, is threadedly mounted block 8, which has an inset cut 9 externally longitudinal of the lower portion thereof, providing 35 shoulders 9a intermediate its top and bottom, in side elevation, said block 8 mounting a pair of elongated pins 10 in spaced relative parallelism, and substantially parallel with shaft 1, said pins 10 being preferably slightly 40 bevelled at their points 10a, adapted to receive and support a matrix band, the respective ends 12 and 13 of which have spaced openings 14 to receive said pins therethrough. Threadedly mounted on the shaft 1, at the 45 other side of its longitudinal center, is a second block 15 which has an opening 16 longitudinally therethrough and an elongated longitudinal trough or channel 17 extending from its lower side substantially parallel 50 with the shaft 1 and adapted to slidably receive and guide within said channel the inset portion 9 of the block 8 disposed below the shoulders 9a, which latter are adapted to slide upon the upper edge surface of the channel 17. This channel 17 and the complementary portion 9 of the block 8 may be formed in any suitable shape, wherein the channel 17 is adapted to receive and guide the block 8, but I prefer a shape arcuate in cross section, as shown in the drawings, since it permits of rounded edges which are preferable in an instrument to be inserted in the mouth.

The opening 16 may be bevelled as at 18 for the purpose of cooperating with the 65 points 10a of the pins 10, to readily effect

alignment when the blocks 8 and 15 are advanced toward each other. A socket wrench (not shown) of any suitable type is used to turnably operate the squared end 5, but such wrench of itself is not a part of this invention.

It is to be understood that the pins 10 and the opening 16, as well as the channel 17 may be optionally transferred for attachment to or as a part of either block, or that the blocks may be transposed in their respective positioning on the shaft, as well as various changes of form, proportion, size and minor details of construction within the scope of the claims, may be resorted to without departing from the spirit or sacrificing any of the advantages of the invention.

In operation, assuming the blocks 8 and 15 to be in contact at the longitudinal center 4 of the shaft 1, and the pins 10 enclosed within the opening 16, the squared end 5 is turned counterclockwise by any suitable means, such as a socket wrench; the threads of shaft 1 being respectively in reverse directions from the portion 4, move the blocks away from each other and thereby draw pins 10 from the openings 16 until the pin points 10a are in spaced relationship to the bevelled end 18 of the opening 16. This permits the perforated ends of the matrix band 11 to be successively mounted over the pins so that the transverse width of the band is transverse the pins. The band is then positioned loosely around the vertical walls of a tooth 19 in a well known manner, and the band is constricted to tight engagement with said vertical tooth walls by turning the shaft 1 clockwise, thus advancing the respective blocks 8 and 15 toward each other and into contact with the respective ends of band 11, and drawing the pins 10 into the opening 16.

It is apparent that as the band is thus tightly drawn around the tooth walls, the band will form an improvised temporary external wall around a cavity 20, permitting a filler material to be placed therein and packed by hammering or other means, without dislodgment or breaking of the filler material. When the dental operation is completed, it is obvious that the band may be removed by reverse turning of shaft 1.

The butting of the shaft at 6 by means of the indentation 7, acts to prevent the block 8 from being threadedly moved beyond the shaft end. It is not necessary to have a similar stop at the opposite end of the shaft 1, since, when block 8 can move no further on the threads, block 15 can move no further, because both move simultaneously by the reverse direction of the threads. For that reason, it is advisable that the division of direction of threads should be at substantially the longitudinal center of the shaft 1. By means of the inter-engagement of the block 8 with channel 17 and the contacting 105

guide formed by the edges 17a of said channel with the shoulders 9a of block 8, the blocks are alignedly guided each by the other and both shaft and block are securely positioned against sidewise movement or turning, the blocks being longitudinally aligned by shaft 1, and thereby maintaining the alignment of the pins 10 with the opening 16. The blocks being moved in opposite directions simultaneously by the right and left 10 thread of the shaft, the relation of their movement either forward or rearward is just twice as fast as though one block were stationary and the movement of the cooperating block were on a one direction thread.

Having thus described the invention, what we claim and desire to secure by Letters Patent is:—

1. A matrix band retainer comprising an aligned axially rotatable shaft, said shaft threaded right hand at one portion thereof and threaded left hand at another portion thereof, a block threadedly mounted on each of said contrary threaded portions of said shaft and provided with opposed faces, said blocks adapted to reciprocate simultaneously in oppositely defined paths upon axial rotation of the shaft, one of said blocks having associated therewith an elongated channel portion adapted to guide said blocks in alignment with relation to each other, pins mounted on one of said blocks adapted to slidably receive and support the ends of a looped matrix band, openings in the other block to releasably engage said pins, the path of movement of said blocks on said shaft being of greater length than the length of the pins.

2. A matrix band retainer comprising an axially rotatable shaft threaded right hand at one portion and threaded left hand at another portion, a block threadedly mounted on each of the contrarily threaded portions of the shaft, said blocks having opposed faces, means projecting from the face of one of said blocks adapted for mounting the respective ends of a matrix band between the opposing faces of said blocks, one of said blocks having an elongated grooved member mounted thereon, adapted slidably to receive and guide the other of said blocks in the reciprocal movement thereof, and said rotatable shaft being positioned between said grooved member and the means to mount the matrix band.

3. A matrix band retainer comprising a shaft, said shaft threaded right hand at one portion thereof and threaded left hand at another portion thereof, a block threadedly mounted on each of said contrary threaded portions of said shaft, mounting means on one of said blocks adapted to mount the respective ends of a matrix band between opposing faces of said blocks, the other block being provided with openings to slidably engage said mounting means, and an elon-

gated grooved member mounted integral with one of said blocks and partially encasing the shaft and adapted for slidably receiving a portion of one block whereby said blocks may be maintained in relative alignment.

In testimony whereof we have signed our names to this specification.

ROBERT R. IMPEY.
